ATTORNEY'S

UNITED STATES PATENT OFFICE.

JOHN P. NEFF, OF EAST ORANGE, NEW JERSEY, ASSIGNOR TO AMERICAN ARCH COMPANY, OF NEW YORK, N. Y., A CORPORATION OF DELAWARE.

ARCH BRICK.

Application filed May 12, 1919. Serial No. 296,294.

To all whom it may concern:

Be it known that I, JOHN P. NEFF, a citizen of the United States, residing at East Orange, in the county of Essex and State of New Jersey, have invented certain new and useful Improvements in Arch Bricks, of which the following is a specification.

This invention has reference primarily to the provision of a brick of the character specified which is intended for use at the side of the arch resting at one end upon a circulation or arch tube and at the other end bearing against a side sheet in the fire box in inclined position.

15 The object of the present invention is to provide a brick which will have a secure bearing upon tubes of various sizes and shapes or curvatures and which will help to hold the brick more firmly in proper position.

20 The above as well as such other objects as may hereinafter appear, I attain by means of a construction which I have illustrated in preferred form in the accompanying drawings wherein:

Figures 1 and 2 are enlarged sectional details of my improved bricks as shown in Figures 3 and 4, illustrating its application in practice adjacent a brick such as is commonly used between arch-supporting tubes; Figure 3 is a sectional view of the brick taken on the line 3—3 of Figure 5; Figure 4 is another longitudinal sectional view through the brick taken on the line 4—4 of Fig. 5; Figure 5 is a plan view of the underside of the brick, and Figure 6 is an elevation of the end which rests against the supporting tubes.

40 Referring now more particularly to Figures 5 and 6, it will be seen that I provide a brick which, at one end, the same being the end adapted to rest against the side sheet, has a narrow portion or edge as at 7 located at the middle of the brick, while on the opposite end adjacent to the sides of the bricks there are projections 8 and 9 with a recess between the said projections extending along the middle part of this end of the brick.

As indicated in Figures 1 and 2 the projections 8 and 9 are formed with a kind of V-shaped bearing which gives two points of support upon the surface of the tube with a clearance space between provided by the recess 11 which is formed with a smaller curvature than the curvature of the tube. The bearing surfaces of the tube engaging end or face of the brick are tangent to the tube and make line contacts therewith. These surfaces are inclined with respect to each other, and, as shown, make approximately or substantially equal angles with the general plane of the brick.

The cut-away portion or recess 10 as indicated most clearly in Figure 4 is extended downwardly to the under face of the brick so as to provide a free passage closely adjacent to the tube. This aids greatly in preventing the choking up of the recess 11 so as to preserve the spaced relation of the bearing projections 8 and 9. Above the lug 9 the surface of the brick is cut back as indicated in Figure 4 to the shoulder 12 so that when the brick is applied as shown in Figures 1 and 2, it will have quite a range of movement 75 angularly around the center of the supporting tube without interfering with the adjacent brick 13.

I claim:

1. A side brick for tube supported fire box 80 arches having at its tube-engaging face tube engaging surfaces arranged and disposed to bear on the tube at circumferentially separated points and making substantially equal angles with the general plane of the 85 brick, and accommodable to tubes of different sizes.

2. A refractory brick for tube supported fire box arches having tube engaging surfaces arranged and disposed to bear on a tube 90 at circumferentially separated points and making substantially equal angles with the general plane of the brick and accommodable to tubes of different sizes.

In testimony whereof, I have hereunto 95 signed my name.

JOHN P. NEFF.
